CLAIM

The ornamental design for a bow tie with an animal head, as shown and described.

DESCRIPTION

FIG. 1 is a top-front perspective view of a bow tie with an animal head, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings depict portions of the bow tie with an animal head that form no part of the claimed design.

The stippling technique applied to the surfaces of the bow tie with an animal head represents a contrast in appearance.
